UNITED STATES PATENT OFFICE.

EDWARD L. HAMILTON, OF McCRRY, ARKANSAS.

DISPLAY-RACK.

1,359,987.

Application filed June 14, 1919. Serial No. 304,235.

Specified of Letters Patent. Patented Nov. 23, 1920.

To all whom it may concern:

Be it known that I, EDWARD L. HAMILTON, a citizen of the United States, residing at McCrry, in the county of Woodruff and State of Arkansas, have invented certain new and useful Improvements in Display-Racks, of which the following is a specification.

This invention relates to storage and display racks and more particularly to a rack for storing and displaying window shades, one of the primary objects of the invention being to provide a rack by which the various colors and styles of shades may be displayed to the best advantage and in which rack a maximum number of shades, duplicates of those on display, may be stored.

Another object of the invention is to provide a rack which will occupy minimum space considering the number of window shades which may be stored therein and which rack will be provided with means whereby the various colors and styles of shades may be supported in precisely the manner in which they would be hung in a window frame so that a customer may gain an excellent idea of the appearance which any shade will have when hung.

Another object of the invention is to provide a rack for the purpose stated which will be extremely simple in its construction and which, if desired, may be shipped in knocked down form and readily set up by the dealer purchasing the same.

35 In the accompanying drawings:

Figure 1 is a perspective view of the rack embodying the present invention;

Fig. 2 is a vertical longitudinal sectional view therethrough;

40 Fig. 3 is a horizontal sectional view on the line 3—3 of Fig. 2;

Fig. 4 is a detail side elevation of one side of the rack.

The rack comprises essentially two side members, indicated in general by the numeral 1, which members are relatively braced in upright parallel relation to each other by means to be presently explained. Each of the side members 1 of the rack 45 comprises side stiles 2, an intermediate stile 3, and cross rails 4, the rails 4 being secured at their ends to the outer sides of the stiles 2 at suitable intervals and extending in a vertical series throughout the height of the 50 said stiles 1, and the intermediate rail 3 be-

ing secured to the mid-portions of the rails 4 at its points of intersection with the said rails. Each side member of the rack further includes a sill 5 to which the lower ends of the stiles 2 and 3 are secured and which constitutes the base of the respective side member. In order that the rack may be conveniently moved about from place to place, rollers 6 are preferably arranged at the ends of the sills 5, as clearly shown in Figs. 1 and 65 2 of the drawings.

Crossed braces 7 and an intermediate brace 8 are secured together midway between their ends in intersecting relation, as indicated by the numeral 9, as for example 70 by a bolt, and the ends of the crossed rails 7 abut against the inwardly presented faces of the sills 5 and are secured thereto as indicated by the numeral 10, preferably, if the rack is to be shipped in knocked down 75 condition, by screws or other fastening elements which may be conveniently driven into place or otherwise secured. Likewise the ends of the cross piece 8 are secured to the sills 5 and preferably to the upper faces 80 of the said sills. In this manner the lower ends of the side members 1 of the rack are secured together and relatively braced, and in order to similarly connect their upper ends, a cross piece 11 is secured at its ends 85 to the upper sides of the uppermost rails 4, preferably by fastening elements of the type before mentioned, if the rack is to be adapted to be knocked down. In order to further brace the side members of the rack, 90 cross braces 12 are secured together in intersecting relation as indicated by the numeral 13 and at their lower ends are secured to the upper side of the cross piece 8 at the ends thereof and also, if desired, to the inner 95 sides of the stiles 3 at the lower ends of the latter. At their upper ends the said cross braces 12 are secured in any suitable manner to oppositely located upper ones of the rails 4 or to the inner sides of the stiles 3 at suitable elevated points. At this point it will be evident that the stiles 3 and cross braces 12 occupy a common plane and that inasmuch as the stiles 3 are located midway between the stiles 2 of the respective side members of the rack and intersect the respective rails 4, each side member of the rack is divided to provide a number of rectangular frame sections 14 within opposite ones of which, in the set up condition of the rack, 110

may be arranged and supported the ends of rolled and, if desired, wrapped shades and their rollers, indicated by the numeral 15.

In order that sample shades and their rollers may be supported for display purposes upon the rack, sets of shade roller brackets 16 are secured upon the ends of the rails 4 of the two side members and in these brackets may be disposed the pintles of the rollers for the sample shades to be displayed in the manner clearly shown in Figs. 1, 3 and 4 of the drawings, so that these sample shades may be drawn down and raised as though hung in a window frame in the ordinary manner. Ordinarily the sample shades will be displayed by drawing each down so that its lower edge portion will lie in advance or overlap the roller of the shade next beneath it, as shown in Fig. 4, so that while all of the shades will be displayed to the best advantage, the shades will also serve to conceal the rolled up and wrapped shades 15 which are arranged within the frame sections 14 as above pointed out. By this arrangement, a sample shade will be hung by its roller in one set of pintles and drawn down to the proper length to overlap at its lower edge the roller next beneath it and in the frame sections immediately rearwardly of the exposed length of this shade may be stored a number of duplicate shades so that when a selection is made by a customer after inspecting the sample shades displayed,

the required number of duplicate shades 35 may be readily removed from the rack by the salesman thus greatly facilitating not only the display of the various colors and styles of shades, but also expediting the filling of the order. 40

Having thus described the invention, what is claimed as new is:

A window shade display rack consisting of spaced side frames each composed of side and intermediate stiles and vertically spaced 45 cross rails secured at their ends and centers to the respective stiles, sills connecting the lower ends of the stiles in each side frame, horizontally disposed braces secured to and extending between the sills, a horizontal 50 brace secured to and extending between the intermediate stiles at the upper ends of the same, vertically disposed cross braces secured to and extending between the intermediate stiles, the stiles and rails defining compartments in which rolled shades may be 55 stored, and shade holders secured to and projecting from the side frames at the upper outer corners of the compartments defined therein whereby sample shades may be 60 hung and displayed in such manner as to cover the compartments respectively containing similar rolled shades.

In testimony whereof I affix my signature.

E. L. HAMILTON. [L.S.]
